UNITED STATES PATENT OFFICE.

CHARLES H. HORNBECK, OF APPLETON, WISCONSIN, ASSIGNEE TO KIMBERLY-CLARK COMPANY, OF NEENAH, WISCONSIN, A CORPORATION OF WISCONSIN.

COLOR DROPPER.

Application filed June 30, 1922. Serial No. 571,936.

To all whom it may concern:

Be it known that I, CHARLES H. HORNBECK, a citizen of the United States, residing at Appleton, in the county of Outagamie and State of Wisconsin, have invented certain new and useful Improvements in Color Droppers, of which the following is a specification.

This invention relates to mechanical fluid droppers but more particularly to such as are suitable for dropping colored fluids upon paper stock in the manufacture of blended papers, and has for its primary object to provide a uniform distribution of the color across the sheet.

Further objects are to provide mechanism which will insure the discharge of the fluid by drops as distinguished from a stream, to permit variation in the rate of dropping to conform to the speed of the paper machine, to eliminate stoppage of or interference with the flow of fluid by sediment, to regulate the head of color solution in the vat, and to permit the application of more than one color solution to the paper stock.

The many other objects and advantages of the invention will be better understood by reference to the following specification when considered in connection with the accompanying drawings illustrating a selected embodiment thereof, in which:

Fig. 1 is a central vertical section of a dropper embodying my invention.

Fig. 2 is a transverse section on the line 2—2 of Fig. 1, and

Fig. 3 is an enlarged vertical section on the line 3—3 of Fig. 2.

Referring to the drawings, the colored fluid is held in a vat 10 and is pumped therein or supplied thereto in any suitable manner. This vat comprises a lower half 11 and an upper half 12 resting on the lower half and secured thereto by means of bolts 13. A series of plates 14 rests on the top of the vat 10 and are preferably provided with suitable notches or grooves 15 to retain them in place.

A shaft 16 extends into the vat 10 and is supported by suitable bearings 17. A packing gland 18 is preferably provided to prevent the escape of the fluid about this shaft. The shaft is preferably driven from a variable speed motor 19 by means of a belt 20 and pulley 21 though it is obvious that any

other suitable form of drive may be provided or the shaft may be geared or otherwise operatively connected to the mechanism of the paper machine (not shown).

In order to provide a distribution of the drops of color across the sheet of paper, a plurality of droppers are provided but as these are identical in construction and mode of operation, only one will be described in detail as this will be equally applicable to the others. The number of these droppers and their spacing on the shaft 16 would depend upon the desired distribution of the color solution on the sheet.

In the dropper mechanism, a collar 25 is secured upon the shaft 16 and this collar is provided with one or more transverse peripheral grooves or slots 26 in the enlarged portion 27 thereof. These slots are four in number in the embodiment shown. A bearing block 28 fits within the lower half of the vat and the central portion of the upper face of this block fits closely the under portion of enlargement 27 of the collar in the manner indicated. A pair of bolts 29 passes through the block 28 and the corresponding plate 14. A spring 30 envelops the projecting upper end of each of these bolts and acts between the upper face of the plate 14 and a winged nut 31 on the bolt to firmly press the block 28 against the collar 25. The bearing block 28 is provided with an outlet passage 32 leading to an outlet pipe 33 screwed into the block. This pipe 33 passes through the bottom wall of the vat and a packing gland 34 is preferably provided to permit a limited longitudinal movement of the pipe with the block without leakage of the fluid. A cock 35 is preferably provided in the lower portion of the pipe 33 so that the flow of fluid therethrough can be stopped. A flexible hose 36 is connected to the lower extremity of the pipe 33 and this hose is provided with a nozzle tip 37. This construction permits the point of application of the drop to be varied somewhat without moving the vat.

In order to permit the head of color solution in the vat to be varied at will, I have provided an advantageous form of adjustable overflow pipe 39 which permits the color solution to be pumped continually into the vat. This overflow pipe passes through the bottom wall of the vat and a packing

gland 40 is provided to permit longitudinal movement of the pipe relative to the vat without danger of leakage of the fluid in the vat. The pipe 39 is raised or lowered in the vat 5 by means of a hand wheel 42 to vary the height of the outflow ports 43 in this pipe. A flexible tube 44 is attached to the lower extremity of the pipe 39 to conduct the overflow to the color supply tank (not shown). 10 A cock 45 is provided to permit the vat to be emptied.

In the operation of the device the paper stock 50 is conducted below the vat 10 on the Fourdrinier wire 51 of the paper machine. As the shaft 16 is rotated, the slots 26 in each of the collars 25 communicate in succession with the corresponding outlet passage 32, allowing a drop of color solution to flow into the pipe 33 and thence down- 20 wardly through the tube 36. This drop is then discharged by the nozzle tip 37 upon the paper as it is forming on the wire.

The rate of dropping is determined by the number of slots in the collar and by 25 the speed of the shaft 16. The amount of color solution that flows through at each communication of a slot depends on the period of communication, the sizes of the outlet passage and slot, the static head of the 30 color solution in the vat and the viscosity of the solution. The sizes of the passage and slot are fixed as is the viscosity, being about the same as that of water at any given temperature. Changes in speed of the shaft 35 to vary the rate of dropping give also changes in the period of communication of the slots which is compensated for by varying the head of the fluid in the vat to give the same sized drop. In this manner the 40 rate of dropping can be varied within wide limits with the size of drop remaining constant. The passages through which the color solution flows are sufficiently large so that danger of plugging is eliminated.

45 The slotted collars are preferably removable. Sets of slotted collars with different numbers of slots can be used and they can be shifted on the shaft so that drops from adjacent nozzles follow each other in 50 any desired succession and at any desired interval. A reference line 55 may be marked upon the shaft parallel with its axis and the slotted collars may be graduated in degrees to facilitate setting at will 55 by calculating the speed of the shaft, the number of slots in the collar, and the angular setting of the collars on the shaft, knowing the diameter of the collar and the speed of the paper machine. Several mechanical 60 color droppers may be mounted side by side with a different color solution in each to give patterns in variegated colors.

I am aware that numerous changes may be made in the form and arrangement of 65 parts without departing from the spirit

of my invention and I reserve the right to make all such as fairly fall within the scope of the following claims.

I claim as my invention:

1. The combination with means for propelling a web, of a vat disposed above the path of said web, and means for providing an intermittent discharge of fluid from said vat upon said web including a discharge passage leading from said vat, and valve 70 mechanism operating in said vat to control the admission of fluid to said discharge passage.

2. The combination with means for propelling a web, of a vat disposed above the 80 path of said web, and means for providing a periodic discharge of fluid from said vat upon said web including a series of discharge passages leading from said vat and disposed at intervals transversely of said path, 85 a shaft revoluble in said vat, and means actuated by said shaft for controlling the admission of fluid to each of said passages.

3. The combination with means for propelling a web, of a vat disposed above the 90 path of said web, and means for providing an intermittent discharge of fluid from said vat upon said web, including a series of discharge passages leading from said vat and disposed at intervals transversely of 95 said path, a power driven shaft revoluble within said vat, and rotary valves upon said shaft for controlling the admission of fluid to each of said passages.

4. The combination with means for propelling a web, of a vat disposed above the path of said web, and means for providing an intermittent discharge of fluid from said vat upon said web, including a series of discharge passages leading from said vat and disposed at intervals transversely of said path, a power driven shaft revoluble within 105 said vat, and slotted collars on said shaft controlling the admission of fluid to each of said passages.

5. A color dropper for paper machines comprising a vat, a revoluble shaft within said vat, a collar on said shaft having one or more transversely extending peripheral slots or grooves therein, a bearing block 115 in said vat closely fitting the cylindrical portion of the periphery of said collar, and a discharge passage in the bearing face of said block normally closed by said collar but communicating with the interior of said vat when a groove in said collar is opposite thereto.

6. A color dropper for paper machines comprising a vat, a revoluble shaft within said vat, a collar secured on said shaft and having one or more transversely extending peripheral slots or grooves therein, a bearing block in said vat closely fitting the cylindrical portion of the periphery of 120 said collar and yieldingly pressed against 125 the bearing face of said collar.

- the same, a discharge port in the bearing face of said block normally closed by said collar but communicating with the interior of said vat to receive a limited quantity of
- 5 fluid therefrom when a groove in said collar is opposite thereto, and a discharge pipe projecting through the wall of said vat with its inner end secured to said block in communication with said discharge port.
- 10 7. A color dropper for paper machines comprising a vat, a revoluble shaft within said vat, a collar secured on said shaft and having one or more transversely extending peripheral slots or grooves therein, a bearing block in said vat closely fitting the cylindrical portion of the periphery of said collar and yieldingly pressed against the same, means for adjusting the pressure of
- said block on said collar, a discharge port in the bearing face of said block normally closed by said collar but communicating with the interior of said vat to receive a limited quantity of fluid therefrom when a groove in said collar is opposite thereto, and a discharge pipe projecting through the wall of said vat with its inner end secured to said block in communication with said discharge port.
- 15 8. A color dropper for paper machines comprising a vat, an overflow pipe projecting into said vat and adjustable therein to vary the depth of fluid in said vat, one or more discharge passages leading from said vat, and means for providing an intermittent flow of fluid through said passages.

CHARLES H. HORNBECK.
